US0D1101102S

(12) **United States Design Patent** (10) **Patent No.:** **US D1,101,102 S**
(45) **Date of Patent:** **** Nov. 4, 2025**

(54) **WATER FILTER**

(71) **Applicant:** **KOROS TECHNOLOGY (SHENZHEN) CO. LTD**, Shenzhen (CN)
(72) **Inventor:** **Huaping Wu**, Shenzhen (CN)
(73) **Assignee:** **KOROS TECHNOLOGY (SHENZHEN) CO. LTD**, Shenzhen (CN)

(**) **Term:** **15 Years**

(21) **Appl. No.:** **29/929,409**

(22) **Filed:** **Feb. 21, 2024**

(51) **LOC (15) Cl.** **23-01**
(52) **U.S. Cl.**
USPC **D23/209**

(57) **CLAIM**

The ornamental design for a water filter as shown and described.

DESCRIPTION

FIG. 1 is a bottom, rear, right side perspective view of a water filter, showing the claimed design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.
The dashed broken lines in the drawings depict portions of the water filter that form no part of the claimed design.

1 Claim, 7 Drawing Sheets
